(57) **CLAIM**

The ornamental design for a security tag with electronic display, as shown and described.

DESCRIPTION

FIG. 1 is a front, left perspective view of a security tag with electronic display showing our new design;

FIG. 2 is a front, bottom, left perspective view thereof;

FIG. 3 is a rear, bottom, right perspective view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a front elevation view thereof; and,

FIG. 9 is a rear elevation view thereof.

The broken lines illustrate portions of the security tag with electronic display that form no part of the claimed design.

1 Claim, 5 Drawing Sheets
